FRANK KRICH, OF NEW YORK, N. Y.

SAFETY-EXTINGUISHER FOR LAMPS.

1,115,214.

Specification of Letters Patent. Patented Oct. 27, 1914.

Application filed June 10, 1914. Serial No. 844,173.

To all whom it may concern:

Be it known that I, FRANK KRICH, a subject of the King of Hungary, and a resident of the city of New York, borough of the Bronx, in the county of Bronx and State of New York, have invented a new and Improved Safety-Extinguisher for Lamps, of which the following is a full, clear, and exact description.

10 The object of the invention is to provide a new and improved safety extinguisher for lamps burning oil, petroleum and like liquids and arranged to automatically extinguish the burner flame in case the lamp 15 is upset, to allow of carrying the lighted lamp about by a person without automatically extinguishing the burner flame, but in case the person carrying the lighted lamp stumbles and loses hold on the lamp then 20 the flame is automatically extinguished.

In order to produce the desired result use 25 is made of a spring-pressed extinguishing member adapted to pass over the burner wick, a movable rod connected with the said extinguishing member to normally hold the latter in open position, and an actuating device for the said rod and normally held 30 in inactive position as long as the lamp rests with its base on a table or other suitable support. Use is also made of a manually 35 controlled locking device adapted to engage and lock the said actuating device with a view to hold the latter and the extinguishing member in inactive position at the time the lamp is carried around by a person.

A practical embodiment of the invention is represented in the accompanying drawings forming a part of this specification, in which similar characters of reference indicate corresponding parts in all the views.

40 Figure 1 is a sectional side elevation of the safety extinguisher as applied to a lamp of usual type; Fig. 2 is a similar view of the lamp extinguisher with the extinguishing member in closed position; Fig. 3 is a side elevation of the extinguishing member attached to the wick tube; and Fig. 4 is a plan view of the same.

The safety extinguisher is shown applied 50 to a petroleum lamp of the usual construction, having a base A, a body B containing a fount or reservoir C for the oil and a burner C' including a wick D, a wick tube D' and a wick raiser D², and carrying a 55 chimney support E. A wick-extinguishing

member F of approximately U shape is provided at its side arms F' with segmental slots F² engaged by pivots F³ secured to the edges of the wick tube D' to allow the extinguishing member F to swing from normal open position, as shown in Fig. 1, into closed position, as shown in Fig. 2. When in this latter position the middle portion F⁴ of the extinguishing member F is on top of the wick tube D' and its wick so as to extinguish the flame emanating from the said wick. Springs G are connected with the side arms F' of the extinguishing member F to pull the latter downward into closed position after the extinguishing member has swung from open position into closed position. The lower ends of the springs G are attached to the edges of the wick tube D', as plainly indicated in Fig. 3, and one side of the middle portion F⁴ of the extinguishing member F is provided with a slotted extension F⁵ engaged by a loop H' of an arm H secured to the upper end I' of a vertically disposed rod I extending into a tube J arranged within the body B and the fount C of the lamp. The upper end I' of the rod I preferably screws on the latter to allow accurate adjustment of the rod I relative to the member F. The lower end of the rod I is provided with a rack I² in mesh with one side of a pinion K journaled in the tube J. The other side of the pinion K is in mesh with a rack L' arranged on the upper end of a second rod L disposed vertically and mounted to slide in the tube J. The lower end of the rod L is adapted to project beyond the under surface of the base A of the lamp and the said rod L is pressed on by a spring N to move the rod L downward whenever the lamp is tilted or lifted off the table or other support on which the lamp is resting at the time. It will be noticed that when the lamp is resting on a suitable support the weight of the lamp overcomes the spring N so that the rod L is held in uppermost position and the rod I is held in lowermost position whereby the extinguishing member F is held in open position relative to the wick tube D'. Now when the lamp is tilted or lifted off the table then the spring N imparts a downward movement to the rod L whereby the pinion K is turned and the rod I is moved upward thus swinging the extinguishing member F upward into closed 105 position.

position relative to the wick tube D' to extinguish the wick flame. From the foregoing it will be seen that by the arrangement described the extinguishing member F is normally in open position as long as the lamp rests on the table or other suitable support, the said extinguishing member F not interfering in the slightest with the ignition of the wick whenever it is desired 10 to do so. When the lamp is accidentally tilted or upset for any reason whatever then the rod L is released and moves downward by the action of the spring N to cause the extinguishing member F to swing upward 15 into closed position with a view to extinguish the wick flame, as above described.

In order to allow of safely carrying the lighted lamp about from one place to another, use is made of a manually controlled locking 20 device for locking the rod L in its normal uppermost position, as shown in Fig. 1. For the purpose mentioned the lower end of the rod L is provided with a notch L² adapted to be engaged by a spring-pressed 25 locking bolt O mounted to slide horizontally in the base A of the lamp, the bolt O being provided at its outer end with a fingerpiece O' adapted to be pressed by the person when taking hold of the lamp in order to lift the 30 same off the table or other support and carry it to a distant place. Normally the bolt O is in retracted position relative to the notch L² by the use of a spring P pressing the bolt O in an outward direction and hence the bolt 35 O does not interfere with the rod L and allow the latter to move downward by the action of its spring N in case the lamp is tilted or upset on the table on which it is resting at the time. When a person desires 40 to carry the lighted lamp about it is necessary to press the fingerpiece O' inward to engage the bolt O with the registering notch L² prior to lifting the lamp from the table or support. Now in case the person carrying the 45 lighted lamp should stumble and release the fingerpiece O' then the spring P immediately retracts the bolt O thus unlocking the rod L. When this takes place the spring N moves the rod L downward and the extinguishing member F is swung from its normal 50 position into closed position to extinguish the wick flame thus preventing explosion of the oil and setting fire to the surroundings.

55 Having thus described my invention, I

claim as new and desire to secure by Letters Patent:

1. In combination with a lamp of the type described, a U-shaped spring-pressed extinguishing member pivoted on the wick tube of the lamp and adapted to swing over the top of the wick tube, a rod connected with the middle portion of said extinguishing member and provided with a rack at its lower end, a spring-pressed operating rod adapted to extend below the bottom of the base of the lamp and provided with a rack at its upper end, and a pinion mounted to turn and in mesh on opposite sides with the said racks. 70

2. In combination with a lamp of the type described, a U-shaped spring-pressed extinguishing member pivoted on the wick tube of the lamp and adapted to swing over the top of the wick tube, a rod connected with the said extinguishing member and provided with a rack at its lower end, a spring-pressed operating rod adapted to extend below the bottom of the base of the lamp and provided with a rack at upper end and with a notch 75 at its lower end, a pinion mounted to turn and in mesh on opposite sides with the said racks, and a manually controlled spring-pressed locking rod adapted to engage the notch of the said operating rod to lock the 80 latter in inactive position.

3. The combination with a lamp, of a U-shaped extinguishing member having segmental slots in its arms, pivots on the wick tube and engaging the slots of the arms of the said member, springs secured to the wick tube and to the arms of the extinguishing member, a rod having its upper end connected with the middle portion of the said member and provided with a rack at its lower 95 end, a sliding and spring pressed operating rod adapted to extend below the bottom of the base of the lamp and provided with a rack at its upper end, a pinion between the rods and in mesh with the racks thereon, and a manually controlled locking device for the 100 operating rod.

In testimony whereof I have signed my name to this specification in the presence of two subscribing witnesses.

FRANK KRICH.
